(57) **ABSTRACT**

A new and distinct *Paulownia* hybrid tree named 'WEGROW-B7' which is characterized by a fast rate of growth, developing a large diameter trunk in a relatively short period of time, an upright trunk with a narrow canopy, and high frost tolerance. The claimed plant propagates successfully by softwood stem cuttings and has proven to be uniform and stable in the resulting generations.

3 Drawing Sheets

1

Latin name of the genus and species: The Latin name of the genus and species of the novel variety disclosed herein is *Paulownia* hybrid.

Variety denomination: The inventive variety of *Paulownia* hybrid disclosed herein has been given the variety 5 denomination 'WEGROW-B7'.

BACKGROUND OF THE INVENTION

Parentage: The claimed tree is a spontaneous whole-plant mutation of an unnamed and unpatented *Paulownia elongata* x *Paulownia fortunei* hybrid plant which was discovered by the inventor in the summer of 2012 at a commercial tree farm in Bonn, Germany. The mutation was noted for its fast rate of growth, near vertical trunk and narrow foliar canopy.

Asexual Reproduction: In the summer of 2012, 'WEGROW-B7' was first asexually reproduced by way of meristematic tissue culture micropropagation in Bonn, Germany. The claimed tree was found to asexually reproduce in uniform and stable manner and 6 successive cycles of vegetative propagation have proven to be true to type.

SUMMARY OF THE INVENTION

The following characteristics have been repeatedly observed and represent the distinguishing characteristics of the new *Paulownia* tree, 'WEGROW-B7'. These traits, in combination, distinguish 'WEGROW-B7' as a new and distinct cultivar.

1. 'WEGROW-B7' exhibits an upright trunk with a narrow canopy which, in cultivation for timber production, equates to a higher planting density and a lesser pruning requirement; and
2. 'WEGROW-B7' develops a large diameter trunk in a relatively short period of time which, in cultivation for timber production, equates to a relatively short production cycle; and

2

3. 'WEGROW-B7' exhibits large, medium green leaves; and
4. 'WEGROW-B7' exhibits frost tolerance to minus ten degrees Celsius.

BRIEF DESCRIPTION OF THE FIGURE

FIG. 1 illustrates, as nearly true as it is reasonably possible to make the same in color photographs of this type, 10 a field-grown 'WEGROW-B7' tree at approximately 3.5 years of age, during spring in Tonisvorst, Germany.

FIG. 2 illustrates, as nearly true as it is reasonably possible to make the same in color photographs of this type, 15 the exemplary mature foliage of 'WEGROW-B7'.

FIG. 3 illustrates, as nearly true as it is reasonably possible to make the same in color photographs of this type, 20 the oldest wood of a mature field-grown 'WEGROW-B7' tree.

BOTANICAL DESCRIPTION OF THE PLANT

The following is a detailed botanical description of a new and distinct *Paulownia* hybrid plant known as 'WEGROW-B7'. Plant observations were made on a 3.5 year-old field-grown tree in Tonisvorst, Germany. The observed tree was 25 grown in full exposure to natural sunlight, and maintained with drip irrigation. No pest or pathogen countermeasures were employed. Two years after planting the observed tree into the field, the tree was pruned to the soil level in May of 2018 and allowed to regrow for approximately 1.5 years. Observation data was then recorded in November of 2019.

Those skilled in the art will appreciate that certain characteristics will vary with older or, conversely, younger plants. 'WEGROW-B7' has not been observed under all possible environmental conditions. Where dimensions, sizes, colors and other characteristics are given, it is to be understood that such characteristics are approximations or averages set forth as accurately as practicable. The phenotype of the variety may vary with variations in the environ-

One' (Community Plant Variety Rights grant number 39980). A comparison of 'WEGROW-B7' with *Paulownia* 'Phoenix One' is described in Table 2.

TABLE 2

Characteristic	'WEGROW-B7'	'Phoenix One'
Rate of growth.	Faster than 'Phoenix One'.	Slower than 'WEGROW-B7'.
General coloration of the mature foliage.	Lighter shade of green compared to 'Phoenix One'.	Darker shade of green compared to 'WEGROW-B7'.

TABLE 2-continued

Characteristic	'WEGROW-B7'	'Phoenix One'
Width of tree canopy.	Narrower than 'Phoenix One'.	Wider than 'WEGROW-B7'.

That which is claimed is:

1. A new and distinct variety of *Paulownia* hybrid tree 10 named 'WEGROW-B7', substantially as described and illustrated herein.
